(57) **ABSTRACT**

A method for driving a cold cathode flat fluorescent lamp (CCFL). The method comprises the steps of generating a pulse-combined signal, applying the pulse-combined signal to an inverter driver circuit which is electrically connected to the CCFL and causes it to light up, and adjusting the pulse width and the pulse period so that the CCFL is at a maximum luminance while a luminance uniformity thereof is maximum. Based on the pulse width and the pulse period, the luminance uniformity of the CCFL is constant while the CCFL is adjusted for a desired luminance.

FIG. 5

METHOD FOR DRIVING A FLAT-TYPE LAMP

BACKGROUND OF THE INVENTION

1. Field of the Invention

The present invention relates to a method for driving a cold cathode flat fluorescent lamp (CCFL) and, more particularly, to a method for driving a CCFL that enables the luminance uniformity of the CCFL to be substantially constant while the CCFL is adjusted for a desired luminance. Specifically, the method improves the luminance uniformity of the CCFL when it is dim.

2. Description of the Related Art

The cold cathode flat fluorescent lamp (CCFL) is used as a back-light source for an LCD display device or an LCD projector, or as a light source for a vehicle. The general construction of a CCFL **100** is shown in FIG. 1, which is provided with a luminous surface **101**, and a pair of electrodes **102** and **103**. A conventional driving apparatus for the CCFL **100** is composed of a power supply **104**, a pulse generator **105**, and an inverter driver **107**, as shown in FIG. 2. In the conventional driving apparatus for the CCFL **100**, a conventional driving method for the CCFL **100** comprises the steps of generating a pulse signal **106** by the pulse generator **105** of FIG. 2, applying the pulse signal **106** to the inverter driver **107**, and generating a control signal by the inverter driver **107** to drive the CCFL **100** to light up. In general, the control signal generated by the inverter driver **107** is a pulse signal or an alternating signal.

In addition, if it is necessary to adjust the luminance of the CCFL **100**, a pulse width P_w of the pulse signal **106** of FIG. 3 is adjusted so as to alter the luminance of the CCFL **100**. Furthermore, a pulse period P_T of the pulse signal **106** is set to be less than the time of visual persistence for human beings, so that the power consumption of the CCFL **100** with the same luminance is reduced.

Thus, using the conventional driving method for the CCFL **100**, it is possible to alter the luminance of the CCFL **100** and reduce the power consumption thereof by adjusting the pulse width P_w and the pulse period P_T of the pulse signal **106**, respectively. However, due to the characteristic of the CCFL **100**, that is, when the pulse width P_w is lowered to alter the luminance of the CCFL **100**, the luminance at electrodes **102** and **103** are brighter than the luminance at the central region of the luminous surface **101**, such that a non-uniformity of luminance in the CCFL **100** occurs. In addition, since the pulse width P_w is lowered compared to the same pulse period P_T , the effective pulse period becomes longer, that is, it is equal to, or longer than, the time of visual persistence for human beings, thereby unstable luminance of the CCFL **100** occurs.

Therefore, it is difficult to have a desired luminance uniformity while the CCFL is adjusted for a desired reduced luminance using the conventional driving method for the CCFL.

SUMMARY OF THE INVENTION

It is an object of the invention to provide a method for driving the cold cathode flat fluorescent lamp (CCFL) for enabling the luminance uniformity of the CCFL to be substantially constant while the CCFL is adjusted for a desired luminance.

It is another object of the invention to provide a method for driving the CCFL suitable for improving the luminance uniformity of the CCFL when it is dim.

It is still another object of the invention to provide a method for driving the CCFL suitable for reducing the power consumption thereof and preventing the luminance of the CCFL from being unstable.

According to an aspect of the invention, there is provided the method for driving the CCFL comprising the following steps: generating a pulse-combined signal, wherein the pulse-combined signal has a plurality of pulse signals, and each of the plurality of pulse signals has a pulse width and a pulse period; applying the pulse-combined signal to the inverter driver circuit, wherein the inverter driver circuit has a pair of output terminals, which are electrically connected to a pair of input terminals on the CCFL so as to input a control signal to the CCFL to light it up; adjusting the pulse width and the pulse period so that the CCFL is at a first luminance while a first luminance uniformity thereof is maximum; setting the pulse width and the pulse period such that the CCFL is at the first luminance and have the first luminance uniformity; and generating the pulse-combined signal having a turn-off time that allows the CCFL to be at a second luminance and to have a second luminance uniformity; wherein the second luminance uniformity is substantially equal to the first luminance uniformity.

It is preferred that the step of generating the pulse-combined signal having the turn-off time comprises using a sinusoid-wave signal, a square-wave signal, or a triangle-shaped wave signal, and performing a modulating operation.

It is advantageous that the method for driving the CCFL further comprises a step of generating the pulse-combined signal having a turn-on time that allows the CCFL to be at a third luminance and to have a third luminance uniformity; wherein the third luminance uniformity is substantially equal to the first luminance uniformity.

It is preferred that the step of generating the pulse-combined signal having the turn-on time comprises using a sinusoid-wave signal, a square-wave signal, or a triangle-shaped wave signal, and performing a modulating operation.

It is preferred that the third luminance is the desired luminance of the CCFL.

It is preferred that the third luminance is the first luminance of the CCFL.

It is preferred that the first luminance is the maximum luminance of the CCFL.

It is preferred that the second luminance is the desired luminance of the CCFL.

Other objects and advantages of the present invention will become apparent from the detailed description to follow taken in conjunction with the appended claim.

DETAILED DESCRIPTION OF THE PREFERRED EMBODIMENT

FIG. 4 is a block diagram showing an example of the method for driving the CCFL **200** according to the invention. As these devices are the same as those in FIG. 2 except of a signal-generating unit **205**, an explanation of them is omitted here.

In FIG. 5, the signal-generating unit **205** is enabled by an enabling signal provided by a power supply **204** so as to generate a pulse-combined signal **206**, wherein the pulse-combined signal **206** has a plurality of pulse signals, and there is a turn-on time T_{on} or a turn-off time T_{off} in the pulse-combined signal **206**. Further, there are a plurality of successive pulse signals during the turn-on time T_{on} ; meanwhile, each of the plurality of successive pulse signals is provided with a pulse width P_w and a pulse period P_T .

Preferably, the turn-on time T_{on} , the turn-off time T_{off} , the pulse width P_w , and the pulse period P_T as above-mentioned are adjusted and controlled by the signal-generating unit 205. According to the description of the method for driving the CCFL 200 as follows, the signal-generating unit 205 is allowed to generate the pulse-combined signal 206 having an adequate pulse width P_w , an adequate pulse period P_T , and an adequate turn-on time T_{on} or turn-off time T_{off} , which is subsequently input to an inverter driver 207. Based on the pulse-combined signal 206, the inverter driver 207 generates a control signal, preferably, a pulse signal or an alternating signal, so that the CCFL 200 is driven to light up. In this way, by controlling the signal-generating unit 205 to generate the pulse-combined signal 206, it is possible to desirably adjust the luminance of the CCFL 200 while the luminance uniformity of the CCFL 200 substantially remains at the maximum.

As described above, the adequate pulse width P_w and the adequate pulse period P_T of the pulse-combined signal 206 generated by the signal-generating unit 205 are corresponded to allow the CCFL 200, regardless of any luminance thereof, to have a substantially constant luminance uniformity. On the other hand, either the turn-on time T_{on} or the turn-off time T_{off} of the same is corresponded to allow the CCFL 200 to be at a desired luminance, wherein the signal-generating unit 205 generates the pulse-combined signal 206 having either the turn-on time T_{on} or the turn-off time T_{off} by using any kind of alternating signal (such as a sinusoid-wave signal, a square-wave signal, or a triangle-shaped wave signal) and performing a modulation. Specifically, if there is no turn-off time T_{off} , the CCFL 200 is at maximum luminance; and if there is no turn-on time T_{on} , the CCFL 200 is at minimum luminance.

The signal-generating unit 205 is any electronic combination composed of electronic devices that can generate the waveform shown in FIG. 5, and it should be understood by a person skilled in the art that the signal-generating unit 205 is not restricted to a particular one, i.e., it could be any electronic circuit that can generates the pulse-combined signal 206.

Referring to FIGS. 4 and 5, the method for driving the CCFL is described according to one embodiment of the invention. Firstly, as shown in FIG. 4, a set of pulse signals is generated by the signal-generating unit 205, wherein the set of pulse signals has a plurality of successive pulse signals, and each pulse signal has a pulse width P_w and a pulse period P_T shown in FIG. 5. Secondly, the set of pulse signals is applied to the inverter driver 207, and based on the set of pulse signals, the inverter driver 207 generates a control signal, preferably a pulse signal or an alternating signal, so that the inverter driver 207 can drive the CCFL 200 to light up.

After the CCFL 200 is driven to light up, the pulse width P_w and the pulse period P_T are adjusted so as to allow the CCFL 200 to be substantially at a first luminance thereof, wherein the first luminance is substantially equal to the maximum luminance of the CCFL 200. Subsequently, the values of luminance of a plurality of regions on the luminous surface are measured; preferably, the number of the plurality of regions is 9. Then, luminance uniformity is defined by calculating the ratio of the value of the minimum luminance to the value of the maximum luminance within a plurality of regions. In a case of keeping the maximum luminance of the CCFL 200 substantially constant, the pulse width P_w and the pulse period P_T are adequately and repeatedly adjusted so as to allow the luminance uniformity to substantially equal a first luminance uniformity, wherein the first lumi-

nance uniformity is substantially equal to the maximum luminance uniformity of the CCFL 200.

Then, the pulse width P_w and the pulse period P_T are set in order to subsequently adjust the desired luminance of the CCFL 200. After that, the signal-generating unit 205 is firstly allowed to use any kind of alternating signal (such as a sinusoid-wave signal, a square-wave signal, or a triangle-shaped wave signal) and to perform a modulating operation, so that the pulse-combined signal 206 having a turn-off time T_{off} is generated. Then, the pulse-combined signal 206 having a turn-off time T_{off} is input to the inverter driver 207 so as to reduce the luminance of the CCFL 200. Lastly, it is allowable to repeatedly input the pulse-combined signal 206 having either the turn-on time T_{on} or the turn-off time T_{off} to the inverter driver 207, so that the luminance uniformity of the CCFL is substantially constant while the same is adjusted for the desired luminance; meanwhile, the pulse-combined signal 206 having a turn-on time T_{on} is also generated by the signal-generating unit 205 using any kind of alternating signal (such as a sinusoid-wave signal, a square-wave signal, or a triangle-shaped wave signal) and performing a modulating operation. This method is suitable for improving the luminance uniformity of the CCFL when it is dim.

According to the embodiment of the invention, it is preferred that a frequency of pulse corresponding to the pulse period P_T is adjusted to a level of more than 60 Hz. In addition, according to the method of the invention, it is possible that the luminance uniformity of the CCFL is substantially larger than 70%.

The invention may be embodied in other specific forms without departing from the spirit or essential characteristics thereof. The embodiment is therefore to be considered in all respects as illustrative and not restrictive, the scope of the invention being indicated by the appended claims rather than by the foregoing description and all changes which come within the meaning and range of equivalency of the claims are therefore intended to be embraced therein.

BRIEF DESCRIPTION OF THE DRAWINGS

FIG. 1 is a schematic diagram of a conventional CCFL;

FIG. 2 is a block diagram of a conventional driving method for a CCFL;

FIG. 3 illustrates the waveform of a conventional pulse signal input to a CCFL;

FIG. 4 is a block diagram showing the driving apparatus and method for a CCFL according to one embodiment of the invention;

FIG. 5 illustrates the waveform of the pulse-combined signal input to a CCFL according to one embodiment of the invention.

What is claimed is:

1. A method for driving a cold cathode flat fluorescent lamp (CCFL), wherein a driver apparatus for the CCFL is composed of a power supply, a signal-generating unit, and an inverter driver circuit, comprising the steps of:

generating a pulse-combined signal having a plurality of pulse signals, wherein each of the plurality of pulse signals has a pulse width and a pulse period;

applying the pulse-combined signal to the inverter driver circuit, wherein the inverter driver circuit has a pair of output terminals, which are electrically connected to a pair of input terminals of the CCFL so as to input a control signal to the CCFL to light it up;

adjusting the pulse width and the pulse period, so that the CCFL can be at a first luminance while a first luminance uniformity thereof is at a substantially maximum level;

- setting the pulse width and the pulse period so that the CCFL is at the first luminance and have the first luminance uniformity; and
- generating the pulse-combined signal having a turn-off time that allows the CCFL to be at a second luminance and to have a second luminance uniformity;
- wherein the second luminance uniformity is substantially equal to the first luminance uniformity.
2. The method as recited in claim 1, wherein the step of generating the pulse-combined signal having the turn-off time comprises using a sinusoid-wave signal, and performing a modulating operation.
3. The method as recited in claim 1, wherein the step of generating the pulse-combined signal having the turn-off time comprises using a square-wave signal, and performing a modulating operation.
4. The method as recited in claim 1, wherein the step of generating the pulse-combined signal having the turn-off time comprises using a triangle-shaped wave signal, and performing a modulating operation.
5. The method as recited in claim 1, wherein the first luminance is substantially equal to the maximum luminance of the CCFL.
6. The method as recited in claim 1, wherein the second luminance is a desired luminance of the CCFL.

7. The method as recited in claim 1, further comprising the step of:
- generating the pulse-combined signal having a turn-on time that allows the CCFL to be at a third luminance and to have a third luminance uniformity;
- wherein the third luminance uniformity is substantially equal to the first luminance uniformity.
8. The method as recited in claim 7, wherein the step of generating the pulse-combined signal having the turn-on time comprises using a sinusoid-wave signal, and performing a modulating operation.
9. A The method as recited in claim 7, wherein the step of generating the pulse-combined signal having the turn-on time comprises using a square-wave signal, and performing a modulating operation.
10. The method as recited in claim 7, wherein the step of generating the pulse-combined signal having the turn-on time comprises using a triangle-shaped wave signal, and performing a modulating operation.
11. The method as recited in claim 7, wherein the third luminance is a desired luminance of the CCFL.
12. The method as recited in claim 7, wherein the third luminance is the first luminance of the CCFL.
